(57) **CLAIM**

The ornamental design for a dual chamber food jar, as shown and described.

DESCRIPTION

FIG. 1 is a perspective view of a first embodiment of the dual chamber food jar;

FIG. 2 is a front view of the first embodiment of the dual chamber food jar;

FIG. 3 is a rear view of the first embodiment of the dual chamber food jar;

FIG. 4 is a left side view of the first embodiment of the dual chamber food jar;

FIG. 5 is a right side view of the first embodiment of the dual chamber food jar;

FIG. 6 is a top view of the first embodiment of the dual chamber food jar;

FIG. 7 is a bottom view of the first embodiment of the dual chamber food jar;

FIG. 8 is a perspective view of the first embodiment of the dual chamber food jar in an opened position;

FIG. 9 is a left side view of the first embodiment of the dual chamber food jar in the opened position; and,

FIG. 10 is a right side view of the first embodiment of the dual chamber food jar in the opened position;

FIG. 11 is a perspective view of a second embodiment of the dual chamber food jar;

FIG. 12 is a front view of the second embodiment of the dual chamber food jar;

FIG. 13 is a rear view of the second embodiment of the dual chamber food jar;

FIG. 14 is a left side view of the second embodiment of the dual chamber food jar;

(Continued)

FIG. 15 is a right side view of the second embodiment of the dual chamber food jar;
 FIG. 16 is an top view of the second embodiment of the dual chamber food jar;
 FIG. 17 is a bottom view of the second embodiment of the dual chamber food jar;
 FIG. 18 is a perspective view of the second embodiment of the dual chamber food jar in an opened position;
 FIG. 19 is a left side view of the second embodiment of the dual chamber food jar in the opened position; and,
 FIG. 20 is a right side view of the second embodiment of the dual chamber food jar in the opened position.
 The broken lines shown in the figures represent portions of the dual chamber food jar that form no part of the claimed design.
